UNITED STATES PATENT OFFICE.

JOHN R. BLAKESLEE, OF CLEVELAND, OHIO, ASSIGNOR TO THE AJAX MANUFACTURING COMPANY, OF CLEVELAND, OHIO, A CORPORATION OF OHIO.

FORGING MECHANISM.

Application filed November 27, 1922. Serial No. 603,451.

To all whom it may concern:

Be it known that I, JOHN R. BLAKESLEE, a citizen of the United States, and a resident of Cleveland, county of Cuyahoga, and State 5 of Ohio, have invented a new and useful Improvement in Forging Mechanism, of which the following is a specification, the principle of the invention being herein explained and the best mode in which I have 10 contemplated applying that principle, so as to distinguish it from other inventions.

The present improvements, relating, as indicated, to forging machines, have more particular regard to the provision in machines of this type of a separable connection between the reciprocable header slide and the pitman. In U. S. Letters Patent 15 No. 737,065, granted to John R. Blakeslee under date of August 25, 1903, there is 20 shown one form of such separable connection which has had an extensive commercial development in a well-known line of forging machines, such connection consisting of a movable auxiliary arm interposed between 25 the pitman and the header slide, the latter being slotted to receive a pin in the pitman which is permitted to reciprocate without moving the die block when such arm is disconnected from the pitman, combined with a 30 slide having an inclined face arranged to be moved into the path of a bearing on said arm, whereby the latter is raised for the purpose in question.

However, in the case of forging machines of large size where all the parts require to be made of very heavy and substantial construction, including such auxiliary arm, the weight of the latter is considerable, due to the length which it must 35 necessarily be given. Furthermore, in order that said arm may be disengaged from the pitman, it requires to be moved through a considerable vertical distance; otherwise it will not clear the latter. Finally, the interposition of such arm, as shown in the aforesaid patent, necessitates the lengthening of the distance between the crank shaft and the slide in order to accommodate such auxiliary arm. The object of the present 40 improved construction has been to eliminate the several difficulties or objections just noted by forming the slot in the slide, wherewith the pin on the pitman engages, on the arc of a circle, thus shortening the 45 rectilinear distance through which the end 50

of the pitman moves relatively to the slide when it is desired to hold the latter stationary. At the same time this permits the employment of a smaller, more compact auxiliary arm in the slide and such arm 60 needs be moved only through a relatively small distance in order to leave the pitman free to reciprocate without moving the slide.

To the accomplishment of the foregoing and related ends, the invention, then, consists of the means hereinafter fully described and particularly pointed out in the claims, the annexed drawing and the following description setting forth in detail certain mechanism embodying the invention, 65 such disclosed means constituting, however, but one of various mechanical forms in which the principle of the invention may be used.

In said annexed drawing:—

Fig. 1 is a broken plan view of a forging machine embodying my present improvements, only the portions of present interest being illustrated; Fig. 2 is a side elevation of the same; and Fig. 3 is a central longitudinal section through the header slide, the plane of the section being indicated by the line 3—3, Fig. 1.

In the several figures of the drawing, only the header slide 1 and the operating mechanism therefor are shown, a broken portion of the supporting framework 2 being indicated in dotted outline in Fig. 2. It will be understood that said slide is reciprocably held in suitable guides, its movement being ordinarily in a horizontal direction, and that suitable means will be provided for securing in the recess 3 in the forward face of said slide the die or dies which may be required for use in the particular 85 operation in hand.

The reciprocatory movement of the slide is derived from a crank shaft 4 that is connected with said slide through the medium of suitable linkage, including the separable 90 connecting means or lock device of present interest. The main element in such linkage is the pitman 5 which is of articulated construction. The respective parts 6 and 7 being hinged together by a pin 8. For the 100 purpose of normally maintaining such parts in rigid relation, so as to make of them a single lever, a latch 9 is pivotally attached to the rear or main part 6, said latch being 105 adapted to engage against an upstanding 110

lug or projection 10 on the part 7 that at the same time serves as a stop to limit the movement of said part upwardly. A compression spring 11 is mounted between latch member 9 and a lug or projection 12 that rises upwardly from the part 6 and serves normally to maintain said latch member in engagement with said lug 10. When, however, the pressure transmitted by the die-block to the end of the forward part 7 of the pitman becomes unduly great so that damage might result, the pressure of spring 11 is overcome and the joint between said part 7 and the main part 6 of the pitman 15 bends upwardly. The foregoing construction, it should be explained, forms the subject-matter of U. S. Letters Patent No. 1,300,240, issued to me under date of April 15, 1919, and is not claimed as a part of the 20 present invention.

The forward end of link or pitman part 7 extends into a recess 15 in the rear part of slide 1 and is pivotally connected to the upper end of a member 16 housed in said part, the lower end of said member being in turn pivotally attached to said die-block 1 by a pin 17. The laterally projecting ends of the pin 18, whereby said part 7 is thus connected to member 16, are received in slots 19 cut in the sides of the slide, such slots being of arcuate form, as shown in Figs. 2 and 3. Inset in the rear end of each slot is a bearing block 20 against which the corresponding end of said pin 18, or rather of the box 21 that surrounds the same, is adapted to contact in the operative condition of the parts shown in full lines in the several figures. Such position of the parts is normally maintained by the engagement of a lock 22 pivotally mounted in the slide about a transverse axis located forwardly of the slots 19 with a notch 23 in member 16. When thus in engagement with such notch, the lock 22 lies in substantially horizontal position, its axis being approximately aligned with the pin 18 as also, for that matter, with the pin 8, which latter serves to connect the two parts of the pitman 5. In such operative position of the parts, said lock, it will be seen, takes a portion of the forward thrust of the pitman, while the bearing blocks 20 take the rearward pulling strain.

Lock 22, however, is freely movable upwardly about its pivotal axis into a position where it is entirely clear from engagement with member 16 and thereupon the latter is adapted to oscillate about its own pivotal axis 17 into the position shown in dotted outline in Figs. 2 and 3. Under this condition, while the pitman is adapted to draw the header slide 1 back to its rearmost position, forward movement of said pitman is ineffective to advance the slide, the only result of continued operation of shaft 4 being

to oscillate member 16 idly back and forth about its axis in the slide 1.

For the purpose of thus lifting the lock 22, substantially the same means are employed as shown and described in Patent No. 737,065, hereinbefore referred to. In other words, a plate 25 is mounted in the frame of the machine in transverse slide bearings (not shown) so as to lie adjacent to the path of movement of slide 1, said plate being formed at its inner end with an inclined face or cam 26. Any suitable means, as for example a treadle or hand lever, may be provided for moving said plate 25 in or out, as occasion may require, in its slide-way. When occupying its innermost position, the inclined face 26 on said plate is disposed to engage with a roller 27 mounted on the free end of a lever 28 that is attached to a rock shaft 29 secured in suitable bearings 30 to the upper face of the die-block or slide 1. There is also fixed to said shaft a second lever 31, approximately parallel with lever 28, that is connected by means of a link 32 with the aforesaid lock 22. As a result upward rocking movement of said first lever, such as will be produced by engagement of the cam face 26 therewith, will be effective to lift said lock, the amount of oscillation imparted being gauged so as to cause said lock entirely to clear notch 23 in member 16.

As a matter of fact, the amount of lift, which is required to be given the lock 22, need not be great, it being sufficient merely to tilt said lock so that when member 16 oscillates about its axis, it will no longer encounter the forward end of the lock. Considerably less clearance, in other words, is required than where the lock engages directly, as in such prior patent, with the longitudinally reciprocable end of the pitman or with a similarly reciprocable member carried thereby. Furthermore, due to the fact that said member 16 is thus oscillatorily mounted in the slide 1, the reciprocable movement of the forward end of the pitman is translated into an oscillatory movement whenever the lock is disengaged and considerably less space is required to accommodate such movement than in the former construction. This renders it possible correspondingly to shorten the slide and renders the construction much more compact in other ways. Finally, the weight of the lock 22 is much less than that of the old lock as it is but a fraction of the length, being ordinarily less than one-half as long.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. The combination with a reciprocable slide; of a crank-shaft and pitman for operating same; a member oscillatorily mounted on said slide, said pitman being pivotally connected with said member; fixed means limiting oscillation of said member in one direction; and movable means adapted to lock said member against oscillation in the opposite direction.

2. The combination with a reciprocable slide; of a crank-shaft and pitman for operating same; a member oscillatorily mounted on said slide about a transverse axis, said pitman being pivotally connected with said member; fixed means limiting oscillation of said member in one direction and a lock pivotally mounted on said slide about a transverse axis and adapted to engage with said member so as to prevent oscillation thereof in the opposite direction.

3. The combination with a reciprocable slide; of a crank-shaft and pitman for operating same; a member oscillatorily mounted on said slide about a transverse axis, said pitman being pivotally connected with said member; fixed means limiting oscillation of said member in a rearward direction; and a lock pivotally mounted on said slide about a transverse axis located forwardly of said member, the latter having a notch opposed to and adapted to be engaged by said lock in one position of the latter, whereby oscillation of said member may be prevented in the opposite direction.

4. The combination with a reciprocable slide; of a crank-shaft and pitman for op-

erating same; a member oscillatorily mounted on a transverse axis in the lower portion of said slide, said pitman being pivotally connected with the upper portion of said member; stops in said slide adapted to limit oscillation of said member in a rearward direction; and a lock pivotally mounted on said slide about a transverse axis located forwardly and above the axis of said member, the latter having a notch opposed to and adapted to be engaged by said lock in one position of the latter, whereby oscillation of said member may be prevented in the opposite direction.

5. The combination with a reciprocable slide; of a crank-shaft and pitman for operating same; a member oscillatorily mounted on a transverse axis in the lower portion of said slide, said pitman being pivotally connected with the upper portion of said member; stops in said slide adapted to limit oscillation of said member in a rearward direction; a lock pivotally mounted on said slide about a transverse axis located forwardly and above the axis of said member, the latter having a notch opposed to and adapted to be engaged by said lock in one position of the latter, whereby oscillation of said member may be prevented in the opposite direction; means carried by said slide adapted to raise said lock; and other means located adjacent the path of movement of said die-block adapted to actuate said last-named means.

Signed by me, this 24th day of November, 1922.

JOHN R. BLAKESLEE.
